Primary Examiner—Bernard Ansher*Assistant Examiner*—Philip Hyder*Attorney, Agent, or Firm*—Bielen, Peterson & Lampe[57] **CLAIM**

The ornamental design for a frame for a physical exerciser, as shown and described.

DESCRIPTION

FIG. 1 is a top right perspective view of a frame for a physical exerciser showing my new design;

FIG. 2 is a right side elevational view, the left side elevational view being a mirror image thereof;

FIG. 3 is a top plan view;

FIG. 4 is a left end view;

FIG. 5 is a right end view; and,

FIG. 6 is a bottom plan view thereof.

FIG. 1

FIG. 5

FIG. 3

FIG. 2

FIG. 4

FIG. 6
